UNITED STATES PATENT OFFICE.

ARTHUR S. LEVY, OF BIRMINGHAM, ALABAMA.

DENTIST'S ANVIL.

1,151,200.

Specification of Letters Patent. Patented Aug. 24, 1915.

Application filed April 3, 1915. Serial No. 18,980.

To all whom it may concern:

Be it known that I, ARTHUR S. LEVY, a citizen of the United States of America, residing at Birmingham, in the county of Jefferson and State of Alabama, have invented 5 certain new and useful Improvements in Dentists' Anvils, of which the following is a specification.

My invention relates to an improved anvil 10 for holding, swaging and attaching posts to backings for interchangeable dental facings.

The object of my invention is to design an anvil which is especially adapted for attaching a novel type of post forming the subject 15 matter of my pending application, Serial No. 17,242, to a backing. I contemplate providing the anvil with sockets adapted to receive posts for both the anterior and posterior facings and in connection with the 20 anterior post sockets I provide a filler plug which is inserted into the socket behind the post, and both the post and the filler block are designed to fill the socket flush with the anvil surface, leaving only the clasp wings 25 projecting above the anvil. The object of this arrangement is to present a smooth flat surface for the reception of the backing from a central point of which surface project the wings on the inserted post that are 30 adapted to be spread by the lead swage block and made fast to the backing. By providing this flat surface to receive the backing, the latter will be made perfectly flat during the swaging operation and no indentations and 35 irregularities in its surface will be produced which might interfere with the proper cementing of the facing to the backing.

I have illustrated the preferred embodiment of my invention in the accompanying 40 drawings which form a part of this specification, and in which:

Figure 1 is a perspective view of the anvil with the filler block removed. Fig. 2 is a plan view showing a post for anterior facings and a filler block in place. Fig. 3 is a 45 partial sectional view on the line $x-x$ of Fig. 2. Fig. 4 is a detail view of the filler block. Figs. 5 and 6 are side and end views of a post for interior facings; and Fig. 7 is 50 a partial sectional view on the line $y-y$ of Fig. 2 showing a post for posterior facings in position.

Similar reference numerals refer to similar parts throughout the drawings.

According to my present invention I provide an anvil of steel or like hard metal hav-

ing in its upper face one or more post receiving sockets. The socket 2 for the post 3 (see Figs. 5 and 6) for attaching anterior facings is formed by an undercut groove 60 leading inwardly from the side edge of the anvil to a point near its center. This groove or socket, in vertical cross section, corresponds to the cross section of the post 3 in a plane below the bases of its wing clasp 65 members 4, the bases of which members lie in the planes of the shoulders 5 which are adapted to abut against the backing and space the rounded post member therefrom. The inner end of the socket 2 is undercut at 70 6 to receive the reduced end shoulder 7 of the post 3. I provide a filler block adapted to fit in the socket 2 behind the post and comprising a rounded head 8 and a narrow vertical web 9 which when inserted stands 75 flush with the top face of the anvil and with the top face of the shoulders 5 of the post. This filler block is removable endwise from the socket so that the posts can be inserted in place and then the filler block introduced 80 behind it so as to co-act with the shoulders 5 of the posts to afford a smooth flat surface for the anvil which will receive the backing 85 10 indicated in Fig. 3, wherein the wings 4 are shown as forced through the backing 90 and ready to be spread by the swage block. The anvil is also provided with a pair of sockets 11 and 12 which are of similar shape but of different sizes, and these are adapted to receive the posts 13 for the posterior facings. These posts 13 have wings 14, similar 95 to the posts 3 and have side members 15, the top surfaces of which lie flush with the top face of the anvil like the shoulders 5.

The socket or slot 3 could be of any length 95 and one or more filler blocks used to fill it out and bring the post to the desired position in the anvil. My improved anvil makes it possible for the dentist to quickly and easily attach either style of post to the backing and at the same time to leave the backing in the desired condition for the application of the solder on the back thereof and the cement on the front face for holding the facing.

Having thus described my invention, what I claim as new and desire to secure by Letters Patent, is:

1. A dentist's anvil having in its upper face an undercut post receiving slot, and 110 means to fill out the slot behind the post flush with the upper face of the anvil.

2. In a dentist's anvil, in combination, an anvil block having in its upper face an undercut slot extending substantially to its center and conforming in vertical cross section to the cross section of the post, and a filler block conforming in cross section to the block and adapted to fill out the slot behind the post flush with the top face of the anvil.
- 10 3. A dentist's anvil having in its upper face a plurality of spaced post receiving

slots, said slots being shaped in cross section to be filled out flush by the posts so as to leave the post attaching means only projecting above the anvil, and a block to fill out the slot for anterior facing posts, substantially as described.

In testimony whereof I affix my signature.

ARTHUR S. LEVY.
